EXTENSIBLE AND RETRACTABLE IMPLEMENT AND CONTAINER THEREFOR

Samuel H. Bobrov, Chicago, Ill.

Application March 15, 1946, Serial No. 654,777

3 Claims. (Cl. 15—258)

1

My invention relates to a combined container and applicator or the like, such as is typically represented by a shoe polish can having a self-contained dauber or applicator carried by the can cover for applying the shoe polish to the shoes. When the cover is in its normal closed position closing the top of the can, the dauber is adapted to occupy a compact retracted position on the under side of the cover and concealed entirely within the can, and when the cover is removed from the can preparatory to applying the polish to the shoes the dauber is adapted to be moved to a projected or outer position extending from the edge of the cover where it can readily serve to apply the polish from the can to the shoes.

One of the principle features of the invention resides in an improved pivotal mounting of the applicator on the can cover. This improved pivotal mounting comprises a pivot member which is disposed in an offset position to one side of the vertical center line of the cover, and which is inclined downwardly and inwardly relatively to said can cover whereby the applicator revolves in an inclined orbit relatively to the cover so that in the closed position of the cover the applicator can occupy this snug compact position substantially up against the under side of the cover, and in the open position of the cover the applicator can be revolved outwardly and downwardly to an operative position projecting a substantial distance from the edge of the cover. The inclined orbit of rotation of the applicator enables it to clear the downwardly turned lip or edge of the cover as the applicator is revolved outwardly to operative position.

Another feature of the invention resides in an improved detent or locking arrangement between the applicator and the lip or flanged edge of the cover, whereby when the applicator is in its outwardly projecting position it will be firmly held in that position by the flanged edge of the cover so that sidewise daubing or rubbing pressure can be transmitted through the cover to the dauber in applying polish to the shoes without causing the dauber to swivel to different positions relatively to the cover.

Another feature resides in combining with this inclined swiveled mounting of the device an extensible arm which enables the applicator to be extended out to a greater distance from the side of the cover.

While I have referred particularly to an applicator for applying shoe polish or the like, the invention also contemplates modified embodiments wherein a measuring spoon, dip or other

2

utility device is employed instead of a dauber and is swung in this same manner from an inner retracted position inside the cover to a downwardly and outwardly projected position outside of the cover.

Other features, objects and advantages of the invention will be apparent from the following detail description of certain preferred embodiments thereof. In the accompanying drawings illustrating such embodiments:

Figure 1 is a plan view of one embodiment of the invention;

Figure 2 is a transverse sectional view taken on the plane of the line 2—2 of Figure 1;

Figure 3 is a fragmentary plan view showing the cover removed from the can and showing the applicator revolved outwardly to its extended position;

Figure 4 is a fragmentary transverse sectional view corresponding to a section taken on the plane of the line 4—4 of Figure 3;

Figure 5 is a transverse sectional view similar to Figure 2 but showing a modified form of handle for the applicator;

Figure 6 is a similar transverse sectional view showing still another form of handle or knob for rotating the applicator;

Figure 7 is a similar sectional view showing another form of handle or knob;

Figure 8 is a similar sectional view showing a modified embodiment characterized by an extensible arm for enabling the applicator or utility device to be extended further from the side of the cover;

Figure 9 shows a different form of utility device which can be substituted for the dauber of Figure 8;

Figure 10 is a plan view similar to Figure 1, but showing a modified mounting of the applicator;

Figure 11 is a transverse sectional view taken on the irregular section plane 11—11 of Figure 10;

Figure 12 is a plan view of another modified embodiment; and

Figures 13 and 14 are detail views showing different mountings of the applicator on the swinging arm.

Referring first to Figures 1, 2, 3 and 4, a conventional container is indicated at 15, this container being shown in the form of a shoe polish can because of the obvious utility of my invention in such type of container, but it will be understood that the invention can also be adapted to other containers as well. This can be pro-

vided with usual form of cover 16 comprising a flat upper portion 17 and a downwardly extending marginal flange 18. The flange 18 is adapted to have a snug frictional fit down over the upwardly extending side wall 19 of the can 15, the lower edge of the flange 18 being adapted to abut an outwardly projecting annular bead 21 in the wall 19 when the cover is in its closed position. The shoe polish contained within the can is indicated at 22, over which is usually placed a disk 10 of waxed paper 23 at the time of filling the can so as to minimize drying of the polish.

Referring now to my improved applicator, the cover 16 is formed with a sloping indentation or bearing surface 25 preferably of circular outline, which is punched or otherwise formed in the top wall 17 of the cover. This sloped indentation is disposed eccentrically in the cover 16, i. e., it is spaced substantially to one side of the vertical axial center line c—c (Figure 2) passing through the center of the cover and can. Extending substantially through the center of this sloping bearing surface 25 is a bearing opening 26 in which is journaled an inclined pivot pin 27 which carries the applicator. In the embodiment shown in Figures 1-4, the pivot pin 27 is inclined downwardly and inwardly relatively to the axial center line c—c, a typical angle of inclination of the pivot pin being indicated by the dash and dot line x—x of Figure 2, the lower end of this axis of rotation x—x either intersecting or extending into close proximity to the vertical center line c—c of the cover. In the embodiment disclosed in Figures 1-4, a vertical plane passing through both the high point and the low point of the sloping bearing surface 25 would also pass radially through the vertical axis c—c of the cover, but as I shall hereinafter describe in connection with Figures 10 and 12, this plane through said high and low points of the inclined bearing surface 25 may be arranged to extend non-radially of the cover. The pivot axis x—x extends substantially at right angles to the sloping bearing surface 25, and upper and lower washers 28 and 29 mounted on the pivot pin 27 engage the top and bottom surfaces of said sloping bearing portion 25. These upper and lower washers are preferably secured to the pivot pin 27, and by their engagement with the top and bottom surfaces of the sloping bearing portion 25 they afford a relatively large area of bearing contact between the cover 26 and the pivot pin 27. The lower bearing washer 29 is shown as being secured to the pivot pin 27 by a soldered attachment 31, but this might be a welded or riveted attachment or any other mechanical attachment. The upper end of the pivot pin 27 is formed with a circular eye 32, and this eye may be likewise soldered, welded, riveted or mechanically fastened in any other manner to the top bearing washer 28. An actuating ring or handle 33 is looped through the eye 32. In its normal folded position this actuating ring 33 lies substantially flat against the top of the cover, approximately as indicated in dotted lines in Figure 2, and in its operative position the ring extends upwardly where it can be readily grasped for rotating the dauber, as indicated in full lines in Figures 2 and 4.

The lower end of the pivot pin 27 is bent laterally to form a relatively long arm 35 which carries the applicator or dauber 36 at its outer end. Referring to the construction shown in Figure 3, the dauber is shown as being formed of a strip of felt which is threaded or pushed over the 70

end of the wire arm 35, following which the arm and strip of felt are bent into the substantially V-shaped outline shown in Figures 1 and 3. However, it will be understood that the invention is not limited to this manner of forming the dauber.

It will be seen that by virtue of the downwardly and inwardly inclined axis of rotation x—x, the dauber 36 will revolve through an inclined orbit of rotation between its inner position shown in Figure 2 and its outer position shown in Figure 4. In the inner position shown in Figure 2, the dauber and the arm on which it is mounted lie substantially parallel to the wall 17 of the can cover and in close proximity thereto, and, in fact, the dauber may be pressed up against this wall 17. Conversely, when the dauber is in its outer or extended position, as shown in Figure 4, the arm 35 and dauber 36 extend downwardly and outwardly at a considerable angle to the can cover, whereby the arm 35 is enabled to clear the marginal flange 18 of the cover. This disposes the applicator 36 in a convenient position relatively to the cover so that it can be readily rubbed across the polish 22 within the body of the can, and then rubbed on the shoes for applying the polish thereto. In such manipulation of the dauber, it can be held in substantially fixed relation to the cover 16 by holding the cover in the palm of the hand with the fingers passing down on opposite sides of the arm 35, or by holding the ring 33. However, I also contemplate providing a detent or locking notch 38 punched out of the lower edge of the marginal flange 18 at a point in the cover where the arm 35 would be extending outwardly across this marginal flange. The arm 35 would then be snapped into this notch 38 when the dauber is swung outwardly to its outer position, the locking relation between the arm 35 and the notch 38 fixedly holding the dauber in extended position relatively to the cover.

In the modified construction shown in Figure 5, the actuating ring 33 has been supplanted by an actuating knob 41 which may be composed of wood, plastic or any other like material. In such construction, the pivot member may consist of a screw 27a passing down through the knob and through the bearing hole 26 in the sloped indentation 25, the lower end of this screw threading into a nut 29a engaging the underside of the sloped indentation or bearing surface 25. The arm 35a may be soldered or welded to this nut 29a, the outer end of said arm having the dauber 36 formed thereon or carried thereby, as previously described.

In the modified construction illustrated in Figure 6, the actuating handle is in the general form of a wing nut 42. The rotatable shaft or pin 27b may consist of a threaded stem extending downwardly from the wing nut 42 and screwing into a lower nut 29b, or it may consist of a threaded shank extending upwardly from the lower member 29b and screwing into the wing nut 42. The arm 35b carrying the dauber 36 is soldered or welded to the lower member 29b.

In the modified construction shown in Figure 7 the actuating handle is shown in the form of a finger piece or lever 43 projecting radially from an upper bearing head or washer 28c. The latter is joined to the lower washer 29c by a pin or screw 27c extending from the upper bearing washer down into the lower bearing washer, or vice versa. The arm 35c is suitably secured to the lower bearing washer 29c. The finger piece

or lever 43 is shown as projecting in the diametrically opposite direction from the arm 35c, which means that this finger piece points radially outwardly with respect to the cover when the dauber is in its inner position. This places the finger piece or lever at a downwardly inclined angle where it can be received in a recessed portion 44 of the cover.

In the modified embodiment shown in Figure 8 the arm carrying the dauber is made extensible so as to enable the dauber to be projected out further from the side of the cover. Any of the previously described forms of actuating handles may be employed, in the particular construction shown the handle 43 having a flanged base portion 47 which bears against the top of the sloping indentation 25. This handle and the lower bearing washer 27d are joined by any suitable bearing pin 27d. The arm 35d, which is suitably secured to the lower washer 27d, may be in the form of a round wire or it may be in the form of a flat strip of metal. Sliding over the projecting end of the arm 35d is an extension tube 51 which carries the dauber 36 at its outer end. For a round wire 35d the tube 51 would be of circular cross section, and for a flat strip 35d the tube 51 would be of flat rectangular cross section. The tube 51 is adapted to be pushed to its innermost position along the arm 35d when the dauber is to be swung up to its inner position under the cover. Conversely, when the dauber is swung outwardly to its outer position, the tube 51 is slid outwardly along the arm 35d to increase the effective distance that the dauber extends from the side of the cover, as illustrated in dotted lines in Figure 8. If desired, the end portion of the arm 35d may be provided with a projecting detent hump 52, and the tube 51 may then be provided with detent recesses 53 and 54 adapted to receive this hump. Such detent arrangement prevents the accidental displacement of the tube 51 entirely off the end of the arm 35d.

As previously described, the invention is also applicable to other types of containers where it may be desirable to provide a measuring spoon, dip or other similar device for use with the contents of the container. In Figure 9 I have shown a measuring spoon 55 provided with an extensible sleeve or tube 51 identical with the extensible sleeve of Figure 8. In such instance, the container may be of appropriate size and shape for containing baking powder, seasoning, condiments, medicinal compounds, or any other materials which it might be desirable to measure by such a measuring spoon 55. This measuring spoon with its extensible sleeve 51 would then be assembled over the arm 35d in lieu of the dauber 36. In some of the appended claims I have used the expression "utility device" to include such dauber 36, measuring spoon 55 and other comparable or like devices.

Figure 10 illustrates a modified construction in which the applicator rotates in an inclined orbit in substantially the same manner as in Figure 1, except that the location and angle of the pivot 27 are so arranged with respect to the cover that the applicator can only be revolved out to its outer position in one direction of rotation, and when the applicator is revolved back to its inner position by rotation in the opposite direction it is brought up against the inside of the marginal flange 18, with the latter then acting as a positive stop. To facilitate understanding of this arrangement, I have shown the cover 16 in Figure 10 as having two imaginary

bisectors y—y and z—z at right angles to each other and both passing through the axial center line c—c of the cover. The pivot 27 for the applicator may be located at any desired point in one of the quadrants between these bisecting lines, but preferably medially and rather close to the marginal flange 18. The angle of this pivot is then made parallel to one of these bisectors so that it does not extend radially of the cover as in Figure 1 but extends on a chord of the cover. In other words, a vertical plane passing through the high and low points of the inclined bearing surface 25 would then extend parallel to the bisector y—y in offset relation therefrom, so that such vertical plane would extend non-radially of the cover, i. e., in the relation of a chord disposed at right angles to the other bisector z—z. In Figure 10 when the applicator is in its inner position, as shown in dotted lines, the arm 35 is disposed substantially in this offset perpendicular plane in which the pivot 27 is inclined. In such arrangement, the applicator or other utility device at the end of the arm 35 is up against the inner side of the marginal flange 18, or in close proximity thereto, when the arm is in its inner position. Thus, the arm cannot be revolved further in a clockwise direction, but when it is to be moved to its outer position it must be revolved in a counter-clockwise direction, whereby the inclined orbit of its path enables it to clear the marginal flange until the upward inclination of its travel brings it back against the lip of the flange. The parts are preferably designed so that this will occur when a substantial length or a maximum length of arm 35 projects outwardly beyond the flange for disposing the applicator as far out as possible from the cover. The full line position of the applicator in Figure 10 represents this optimum position of the applicator, but it will be understood that the applicator arm may be brought to a stop against the lip of the flange 18 at other working angles of the applicator if desired. Several variables control this position, such as the location of the pivot 27, the angle of the pivot, the height of the flange, etc. When in this outer position the engagement of the arm against the lip of the flange 18 positively prevents further movement of the arm in this counterclockwise direction, and the arm may be releasably held against backward movement in a clockwise direction by providing a detent notch 38 in the flange at this point. The arm can then be sprung into this notch. When finished using the applicator, the arm is sprung free of the notch and the applicator is then revolved clockwise back to its inner position. The detailed construction of the pivot arrangement in Figure 11 is shown as corresponding to that of Figure 1 except that the outer end of the pivot 27 is merely riveted over or welded to the outer bearing washer 28, without the provision of any handle. The releasable locking engagement in the detent notch 38 of Figure 11 reduces the need for a handle. However, I wish it to be understood that any of the operating handle or lever embodiments of Figures 1, 5, 6, 7 or 8 can be employed with the construction of Figure 10 if desired.

In Figure 10 I have shown a hinged form of applicator or dauber 61. A suitable backing plate 62 is provided with a bearing sleeve 63 extending across its upper surface, and the arm 35 is provided with a yoke portion 64 extending through this bearing sleeve. Other hinging

arrangements may be employed to provide the hinged mounting on the arm 35. The applicator material is suitably secured to the lower face of the backing plate. This hinged construction enables the applicator surface to lie flat against the surface of the polish or the surface of the shoe irrespective of the angle of the cover when held in the hand. It also enables the applicator to assume a more compact inner position on the under side of the cover when the container is closed. It will be understood that the spoon or dip 55 of Figure 9, or other forms of utility devices, can be employed in the construction of Figure 10.

Figure 12 illustrates the invention adapted to a rectangular or other non-circular form of cover. In this embodiment the pivot 27 is also inclined in a plane perpendicular to the cover and offset from the center of the cover, similarly to the arrangement shown in Figures 10 and 11. This perpendicular offset plane is shown as extending parallel to one of the long dimensions of the cover, i. e. in substantially the plane of the arm 35 when said arm is in its inner position. The arm in its outer position will have engagement against the lip of the flange extending downwardly around the edge of this cover, and may have releasable detent engagement in a detent notch 38 in this flange if desired. The approximate or preferred outer position is illustrated in full lines, but it will be understood that such outer position may be at other angles, as desired. I have shown this utility device as consisting of a spoon 55, but it may be of other forms.

In Figure 13 I have shown a resilient construction of applicator in which spring flexure can occur between the arm 35 and the applicator surface. In this construction the arm 35 is formed with a reversely bent spring end 66 to which is secured a strip 67 composed of spring steel, leather, fiber, plastic, oil resistant rubber stock, or other resilient or yieldable material functioning as a mounting for an applicator surface or functioning as the applicator surface itself. In Figure 14 the construction is very much the same except that the arm 35 is formed with one or more spring loops 69 which give added resiliency to the applicator. These resilient constructions shown in Figures 13 and 14 enable the applicator surface to bear flat against the surface of the polish or the surface of the shoe even if the cover is held at quite an angle of inclination.

I wish it to be understood that the orientation of the pivot 27 and the inner and outer positions of the applicator arm 35 need not be exactly as shown in Figures 1 and 10. For example, in Figure 1, the perpendicular offset plane in which the pivot 27 is inclined can assume any other radial position or angle around the cover, and the inner position of the applicator arm 35 need not coincide with this plane. Also, in Figure 10 it will be understood that the bisecting axes

$y-y$ and $z-z$ are purely imaginary, capable of being shifted to any other positions around the cover, with the perpendicular offset plane of inclination of the pivot 27 assuming any other non-radial position or angle around the cover, and that the inner position of the applicator arm need not coincide with such plane.

While I have illustrated and described what I regard to be the preferred embodiment of my invention, nevertheless it will be understood that such are merely exemplary and that numerous modifications and rearrangements may be made therein without departing from the essence of the invention.

15 I claim:

1. In an apparatus of the class described, the combination with a container, of a cover therefor, pivot means carried by said cover with the rotatable axis offset from the center of the cover and passing obliquely through said cover and inclined downwardly and inwardly relatively to said center, an arm carried by said pivot means on the underside of said cover and having a utility device supported upon said arm, said utility device and arm being rotatable about said pivot axis, the arm extending from the pivot means at such an angle and the pivot axis inclination being such that said arm and utility device may be disposed against the cover in one position and rotated from said one position outwardly away from the cover plane and outside of the border of the cover.
2. The structure according to claim 1 wherein said cover has a downwardly extending marginal flange, the pivot axis inclination being in a non-radial direction so that the pivot axis does not intersect the cover centerline extending through the center of the cover and perpendicular to the plane thereof whereby said arm and utility device may be disposed against said cover as a rest position and rotated in only one direction to clear the flange, reverse direction of rotation from rest position being stopped by said flange.
3. The structure according to claim 1 wherein said cover has an indentation whose surface is inclined with respect to the surface of the cover for supporting and inclining the pivot means.

45 SAMUEL H. BOBROV.
